LÉON HATOT, OF PARIS, FRANCE.

ELECTROMAGNETIC CLOCK.

Application filed February 13, 1924. Serial No. 692,588.

To all whom it may concern:

Be it known that I, LÉON HATOT, citizen of the French Republic, residing at 23 Rue de la Michodière, Paris, France, have invented certain new and useful Improvements in Electromagnetic Clocks, of which the following is a specification.

My invention relates to an electro-magnetic clock comprising an operating pendulum of the known type wherein the circuit-breaker for the supply current which is mounted upon the pendulum device is closed for practically the whole of each successive swing of the pendulum in a given direction.

In this type of clock, the elements of the electromagnetic system such as the permanent magnet and the current coil, are so disposed that the driving effort is exercised upon the pendulum during the whole time of closing of the circuit. If the mechanical resistance of the clockwork should increase, causing a corresponding diminution of the amplitude of oscillation, the counter-electromotive force induced in the solenoid by the motion of the said magnet will be diminished, and the operating current becomes increased, thereby producing a greater power effort which is constantly exercised for a like period, and this tends to restore the normal value of the oscillation.

But in order that this action should be effective and that the amplitude of oscillation shall remain constant, the operating current must increase by a sufficient value. The current will however depend upon the difference between the E. M. F. of the battery and the counter-e.m.f. which is induced, and the current variations due to the variations in the counter-e.m.f. will be more apparent according as the counter-e.m.f. is nearer the voltage of the battery. But in order to provide for a high value of the counter-e.m.f. it becomes necessary to employ magnets and solenoids of large size which are both cumbersome and expensive.

In electric clocks of this type, it is further required that the time of flow of the current shall be exactly constant. The contact arm which is mounted on the pendulum between two stop-pieces, one conducting and the other insulated, can be regulated in a very exact manner for this purpose, and the said arm is given a considerable length and is pivoted at a distance from the axis of oscillation of the pendulum; but in this arrangement the lever arm through which the

mechanical resistance due to the said arm is caused to act upon the pendulum will have a great length, so that the resistance acting against the maintenance of the oscillation will be also considerable.

My said invention has for its object to obviate the above-mentioned drawbacks and to provide for the construction of a clock of small size at a reduced cost. It chiefly consists in the use of an electro-magnetic system wherein the power impulse is produced during a time which is much shorter than the duration of the electric current, i. e. during the passage of the pendulum adjacent the vertical position. In this manner the specified time, which depends essentially upon the disposition of the electromagnetic system, will be exactly constant and hence the circuit-breaker is not required to open and close the circuit with any great precision.

For the circuit-breaker, I may employ a short and light arm which is mounted on the pendulum near its axis of oscillation and which offers but a small mechanical resistance, and this will augment the coefficient of utilization of the electric power. I am enabled to provide an electromagnetic system which receives current during the entire pendulum stroke in a given direction but which develops power only adjacent the vertical position of the pendulum, this being carried out by the use of a relatively flat solenoid so disposed that the end of the magnet shall be engaged therein when the pendulum occupies the vertical position. In this arrangement, the flux in the magnet which is surrounded by the turns of the solenoid will not vary appreciably except when the pole of the magnet passes through the solenoid. The electromagnetic effect is thus manifested as an impulse given to the pendulum when near the vertical position, but it will be practically null during the remainder of the stroke.

In this arrangement, the constant amplitude of the pendulum is not obtained by variations in the counter-e.m.f. which as above stated must have a great value in this case, and for which powerful elements of a large size must be employed, but I obtain the constant amplitude of oscillation by an electromagnetic action of an antagonistic nature which is exercised upon the pendulum solely at the end of its swing in order to insure the damping of its motion, the

action decreasing rapidly when the amplitude exceeds the normal value.

The damping or retarding device may consist of an energized solenoid whose polarity is contrary to that of the operating solenoid, or be a short-circuited solenoid, or again by a tube of non-magnetic metal, and preferably of copper, the said solenoid or tube being so disposed that the end of the magnet shall be engaged therein at the end of a stroke of normal amplitude.

By reason of this modification of the regulating arrangement, and the better use of the electric power, I am enabled to employ a very short pendulum comprising a light magnet, together with a weak solenoid, whereby clocks of very small size but of an accurate nature can be constructed. Due to the light weight of the pendulum, a suspension device can be adopted consisting of loops of steel wire, this being simple as well as strong.

Various constructional features of an improved character, intended either for the reduction of the mechanical resistance, or for simplifying the mechanism and reducing the cost, will be disclosed hereunder.

In this invention, I am chiefly enabled to construct an electric clock mechanism which is contained in a cylindrical case of the same size as those in current use for mechanical clockwork, and which can be substituted for the latter upon the same clock bases.

A simple device for the adjustment for constant amplitude can be constructed by mounting below the pendulum magnet a second magnet whose inclination may be varied.

A constructional form of a small clock in accordance with the invention is shown by way of example in the appended drawings wherein:

Fig. 1 is a section on a vertical diametrical plane passing through the pivoting axis of the pendulum.

Fig. 2 is a front view of the mechanism, with the dial removed.

Fig. 3 is an elevational view showing the battery and the elements for attaching the same as well as for the ready adjustment and transportation; the rear cover of the clock is removed.

Fig. 4 is a transverse section on the line 4-4' of Fig. 3, showing in detail the manner in which the battery is put in operation.

Fig. 5 is a detail section of Fig. 2 through line 5-5 showing on a large scale the suspension of the pendulum, the circuit-breaking element controlled by the pendulum, and the ratchet device controlling the gearing which actuates the clock hands.

Fig. 6 is a section on the line 6-6 of Fig. 5.

Figs. 7 and 8 show two parts of the circuit-breaking element.

Fig. 9 is a view showing the arrangement of the pivoting loops of the pendulum.

Fig. 10 is a diagrammatic view showing the operation of the suspension.

Fig. 11 shows a small clock comprising a base provided with a cylindrical recess into which is fitted the cylindrical casing which contains all the elements of the clock-work as shown in Figs. 1 to 9 and upon whose base is disposed a regulating magnet.

The small clock comprises a cylindrical casing A whose front is constituted by the dial and which contains the clock mechanism.

The pendulum is shown in Figs. 1, 2, 5 and 6. It consists of a strip of metal 1, preferably of invar metal, having at the lower end a magnet 2 in the form of a circular arc whose centre coincides with the axis of motion of the pendulum; the said magnet is secured to the strip 1 by the clamping collar 3. The strip 1 is secured to a member 4 having the form of an inverted U by means of the screw 5; the said screw also maintains a loop 6 of a very hard steel wire having the shape represented on a large scale in perspective in Fig. 9; said loop has the portions a fitting exactly into holes in the strip 1, whereby it is well secured and will not move. To the other end of the member 4 is attached a tempered steel plate 7 by means of the screw 5' which also secures a loop 6' similar to the loop 6. The loops 6 and 6' respectively engage two similar loops 8, 8' situated in a vertical plane perpendicular to the plane of the loops 6, 6'; the loops 8, 8' are held between two brackets 9, 9' by screws 10, 10'; said brackets constitute the fixed support of the pendulum, and are secured to the plate 11 forming the front of the casing A. The dial 12 is attached to said plate, the latter supporting all the elements of the clock.

The movable arm of the electric contact device, which is pivoted to the pendulum, consists of the screw 13, Figs. 5 and 6, having thereon a small ring of a precious non-rusting metal 14; the screw 13 is screwed into a shaft 15 pivoting in apertures in the member 4. At one end of said shaft is mounted the pin 16 whereof the end is in contact with a spring strip 17 exercising a pressure in the direction of the axis of rotation; the other end of the shaft 15 is in contact with the plate 7, and shows a cavity 15', the shape of which is such that it will prevent flowing out of the lubricating oil disposed therein and thereby avoid excessive friction. Friction takes place on the plate 7 upon a relatively large diameter. A small spiral spring 17', Fig. 5, makes electric connection between the pendulum and the support 9; the said spring is so disposed that its centre line coincides with the axis of rotation of the pendulum, and it offers no

disturbance to the operation, working under excellent conditions. Since the spring 17 bears upon the said shaft at a point at which the linear speed is null, there will be no 5 friction nor alternation of the surfaces. A perfect electric connection for the conducting arm is thus obtained by means of these various conditions.

The ring 14 is disposed between two small 10 rods 18, 19, Fig. 6, secured respectively to the plates 20, 21 which are shown separately in Figs. 7 and 8; said plates are mounted on a bracket 22 by the screws 23, 23'. The rod 19 consists preferably of a precious non-rusting metal; the bracket 22 is attached to 15 the base plate 11. The plate 20 is electrically insulated by the insulating pieces 24, 24' and the insulating washers 25.

To the plate 11 is secured a solenoid 26, 20 Fig. 2, comprising two coils 26¹, 26² connected in series but wound in the inverse direction; the coil 26¹ co-operates with one of the pole ends of the magnet 2 when the pendulum is in the vertical position.

The coil 26¹ has a relatively small height, 25 this being such that when the pendulum makes its normal swing, the magnetic flux through the coil will not vary substantially except when near the vertical. When the 30 pendulum is at the end of the stroke in the direction of the arrow *f*, Fig. 2, the pole end will project out of the solenoid; the flux through the solenoid is equal to the flux in the magnet, and remains substantially 35 independent of the angle of the pendulum when above a stated value (3 to 4 degrees in the case of the figure). In like manner, when the pendulum occupies the corresponding angular position on the other side of the 40 vertical, and contrary to the arrow *f*, the pole end will be entirely removed from the solenoid and the magnetic flux through the latter will be practically null. For this reason, when a current is sent through the 45 solenoid during the whole stroke in the direction *f*, electro-magnetic energy will be produced solely when near the vertical. The coil 26² is disposed at the right of the coil 26¹ so that at small amplitudes the coil 50 26² shall be outside of the flux of the magnet, and that this flux shall traverse its wire turns only when the pendulum has moved sufficiently to the right. Further, one may dispose in symmetrical position on the other 55 side of the vertical with reference to the coil 26², a short-circuited coil or simply a metallic tube 27 (preferably of good conducting electrolytic copper).

The source of current consists of a battery 60 28 placed in the rear of the casing A; the terminals 29, 30 of the battery are respectively connected to two spring strips 31, 32; said strips are secured to the base plate 11 and are electrically insulated. One end 65 of the winding 26¹ and 26² is grounded in

the frame and the other end is connected to the contact spring 31. The spring 32 is connected to the insulated plate 20.

During its motion in the direction *f*, the pendulum actuates a ratchet wheel 33, Fig. 70 6, by the pawl 34 mounted on a shaft 35 which is pivoted to the member 4 of the pendulum; the wheel 33 controls the clock hands A¹, A², A³ by means of suitable gearing, Fig. 1. 75

The operation is as follows:

At each stroke of the pendulum in the direction *f*, the conducting arm 13 comes into contact with the rod 19; this closes the circuit comprising the battery and the coils 80 26¹, 26² whereby a magneto-motive force is set up. The windings as well as the direction of the permanent flux of the magnet 2 are so calculated that this force shall have the direction of the motion *f*, and that the 85 electric energy shall exceed the opposing resistances.

In these conditions the amplitude of swing tends to increase, but the augmentation is limited by the action of the coil 26² 90 and the tube 27; for large amplitudes, these latter will set up an antagonistic action, thus providing for a very stable rate of working, as above indicated. This retarding action will be automatically eliminated 95 if the amplitude should decrease by reason of the weakening of the battery or an increase in the friction. An excess of energy is thus available for the maintenance of the 100 operation.

It will be observed that the pivot joint provided for the pendulum acts in the same manner as the knife-edge pivot of the known type in which the knife-edge is slightly rounded; this provides for a rolling motion 105 without friction, Fig. 10. In these conditions there will be no wear as takes place with the usual pivots. The arrangement indicated in the drawings (Figs. 1, 2 and 3) shows that all the elements are disposed so 110 as to occupy a small space.

In order to modify the frequency of the oscillations and thus to advance or set back the clock, two arrangements have been provided:

1. A weight 36 movable on a rod 36' secured to the end of the pendulum, Fig. 1.
2. A stop-piece 37 which is mounted on the lever 38 (Fig. 2) pivoted at O and is urged by a spring strip 39 attached to the 120 pendulum. By turning the lever 38 one can change the position of said stop-piece and hence modify the couple acting upon the pendulum due to the spring 39.

The battery 28 is secured to a plate 40 125 which is connected with the base plate 11 by the supports 41; the plate 40 has therein an aperture *p*, Figs. 1 and 3, whose edges *m*, *n* are raised so as to form a guide for the battery; the latter is held in place by an 130

arm 42 pivoting on an axle 45. To the plate 40 is pivoted an arm 43 movable on an axle 44; the said arms serve to hold the pendulum for transportation purposes, as shown in Fig. 3.

The clockwork can be protected by a glass disc 46 and a rear cover 47; the mechanism is secured to the casing A by hooks 48, Fig. 3, turning upon the screws 49 which also serve to attach the plate 40 to the supports 41; the ends of said hooks engage in holes in the casing A. The cover 47 is secured in place solely by the springs 50, Fig. 1, and it can be removed with great facility.

15 All the complicated parts are disposed between the plates 11 and 40. The apertures 51 and 52 are formed in the plate 40 whereby the regulating lever 38 and the lever 43 holding the pendulum can be operated from 20 the rear of the clock, after removing the cover 47. The battery 28 is set working by simply placing it in the position shown in Fig. 4.

It is observed that all the elements are of 25 a simple and substantial nature and can be readily removed. To remove the mechanism from the casing, it suffices to turn the hooks 48 in the direction $\nearrow$, Fig. 3, and to draw out the plate 40; all the elements will 30 now be quite accessible. An apparatus is thus obtained which can be manufactured in a simple and economical manner.

A device for magnetic regulation is shown 35 by way of example which serves to advance or to set back the clock without interfering with the clockwork properly so called, and it consists essentially of a magnet 55 disposed below the cylindrical casing 56 containing all the elements of the clockwork 40 and which is fitted into a corresponding round recess in a suitable base 57. The magnet 55 has substantially the same length as the pendulum magnet 2; its poles S^2 N^2 are situated respectively below the pendulum 45 magnet poles N^1 S^1 , and exercise thereupon, according to their position in like or contrary polarity, a repulsion or an attraction 50 which modifies the period of the oscillations. This action depends upon the spacing and the position of the magnet 55, and it is chiefly evident when employing a strong magnet 55 having a substantially horizontal position, wherein its poles S^2 , N^2 are respectively in the same vertical line as the 55 poles N^1 , S^1 when the pendulum is at rest. The effect of said magnet upon the pendulum 60 can be very slightly modified by giving to the magnet 55 a very small inclination to the horizontal in either direction, thereby 65 setting the clock forward or back. For this purpose, the magnet 55 is preferably pivoted at one end to a shaft 58, and the other end which serves as a pointer, cooperates with a graduated scale 60 indicating for instance in seconds per day the advance or

retardation due to a given position of the magnet. In this manner it is feasible to maintain the proper adjustment of the clock at all times, in spite of the variations occurring in the battery and the friction.

70 Magnetic regulation has already been provided for electric clocks, wherein a piece of soft iron is placed near the magnet, said piece being disposed in the casing in a position in which it is not subject to interference.

I now substitute for said iron piece a powerful regulating magnet, and the latter can be placed outside of the clock case at a certain distance therefrom, chiefly where the pendulum magnet 2 is (as shown) practically rectilinear, for in this event the action of the magnet 55 on the magnet 2 will preserve its value in spite of a considerable spacing between said magnets. By suitably separating the magnet 55 from the pendulum magnet, it can be mounted outside the clockwork case, in which position it enables a simple and practical adjustment, as shown in Fig. 11.

80 What I claim is:

1. An electromagnetic clock with motive pendulum, comprising a pendulum, a circuit-breaking element mounted upon the said pendulum and closing the supply circuit for practically the entire duration of the successive swings of the pendulum in a given direction, an electromagnetic system consisting of a solenoid of small size connected to the supply circuit and by a light magnet of small size, the said magnet being 90 mounted on the pendulum while the said solenoid is disposed in the path of the magnet, and means whereby the said electromagnetic system shall act upon the pendulum only during a time which is considerably 95 less than the time during which the circuit remains closed, a complementary electromagnetic device exercising a retarding action 100 upon the pendulum when at the end of its normal swing, and means for rapidly 105 increasing the retarding action when the amplitude of swing increases.

2. An electromagnetic clock with motive pendulum, comprising a pendulum, a circuit-breaking element mounted upon the 115 said pendulum and closing the supply circuit for practically the entire duration of the successive swings of the pendulum in a given direction, an electromagnetic system consisting of a solenoid of small size connected to the supply circuit and by a light magnet of small size, the said magnet being mounted on the pendulum while the said solenoid is disposed in the path of the magnet, and means whereby the said electromagnetic system shall act upon the pendulum only during a time which is considerably 120 less than the time during which the circuit remains closed, and devices having an electromagnetic retarding action, wherein the 125

end of the magnet is placed when the pendulum is at the end of its swing of normal amplitude.

3. An electromagnetic clock with motive pendulum, comprising a suspended pendulum, a short and light circuit-breaking arm pivoted to the said pendulum very close to its suspension device, two stationary contacts one of which is included in the electric circuit and between which the said arm is movable, a spring strip provided upon the pendulum and pressing against the end of the pivoting shaft of the said arm, an electromagnetic system consisting of a solenoid of small size connected to the supply circuit and by a light magnet of small size, the said magnet being mounted on the pendulum while the said solenoid is disposed in the path of the magnet, and means whereby the said electromagnetic system shall act upon the pendulum only during a time which is considerably less than the time during which the circuit remains closed, a complementary electromagnetic device exercising a retarding action upon the pendulum when at the end of its normal swing, and means for rapidly increasing the retarding action when the amplitude of swing increases.

4. An electromagnetic clock with motive pendulum, comprising a suspended pendulum, a short and light circuit-breaking arm, a pivoted shaft mounted on said pendulum very close to its suspension device, a spring mounted on the pendulum which forms part of the electric circuit and urges the said shaft upon a very small front end surface of the latter, a bearing surface of relatively large area formed at the rear end of the said shaft, a recess formed in said pendulum and containing the rear end of the shaft, a contact surface provided in said recess and coacting with the rear end of the shaft, an oil cavity formed in said rear end of the shaft, two stationary contact elements one of which is included in the electric circuit and between which the said arm is movable, a spring strip provided upon the pendulum and pressing against the end of the pivoting shaft of the said arm, an electromagnetic system consisting of a solenoid of small size connected to the supply circuit and by a light magnet of small size, the said magnet being mounted on the pendulum while the said solenoid is disposed in the path of the magnet, and means whereby the said electromagnetic system shall act upon the pendulum only during a time which is considerably less than the time during which the circuit remains closed, a complementary electromagnetic device exercising a retarding action upon the pendulum when at the end of its normal swing, and means for rapidly increasing the retarding action when the amplitude of swing increases.

5. An electromagnetic clock with operat-

ing pendulum, comprising a pendulum, loops of a very hard steel wire secured to the upper part of the pendulum and parallel to its plane of oscillation, similar loops of a very hard steel wire secured to the clock frame 70 perpendicular to the plane of oscillation of the pendulum, and engaging the first-mentioned loops, a short and light circuit-breaking arm, a pivoted shaft mounted on said pendulum very close to its suspension device, a spring mounted on the pendulum which forms part of the electric circuit and urges the said shaft upon a very small front end surface of the latter, a bearing surface of relatively large area formed at the rear 80 end of the said shaft, a recess formed in said pendulum and containing the rear end of the shaft, a contact surface provided in said recess and coacting with the rear end of the shaft, an oil cavity formed in said rear end of 85 the shaft, two stationary contact elements one of which is included in the electric circuit and between which the said arm is movable, a spring strip provided upon the pendulum and pressing against the end of the pivoting shaft of the said arm, an electromagnetic system consisting of a solenoid of small size connected to the supply circuit and by a light magnet of small size, the said magnet being mounted on the pendulum 95 while the said solenoid is disposed in the path of the magnet, and means whereby the said electromagnetic system shall act upon the pendulum only during a time which is considerably less than the time during which 100 the circuit remains closed, a complementary electromagnetic device exercising a retarding action upon the pendulum when at the end of its normal swing, and means for rapidly increasing the retarding action when 105 the amplitude of swing increases.

6. An electromagnetic clock with operating pendulum, comprising a pendulum, loops of a very hard steel wire secured to the upper part of the pendulum and parallel to its plane of oscillation, similar loops of a very hard steel wire secured to the clock frame perpendicular to the plane of oscillation of the pendulum, and engaging the first-mentioned loops, a short and light 110 circuit-breaking arm, a pivoted shaft mounted on said pendulum very close to its suspension device, a spring mounted on the pendulum which forms part of the electric circuit and urges the said shaft upon a very 115 small front end surface of the latter, a bearing surface of relatively large area formed at the rear end of the said shaft, a recess formed in said pendulum and containing the rear end of the shaft, a contact surface provided in said recess and coacting with the rear end of the shaft, an oil cavity formed in said rear end of the shaft, two stationary contact elements one of which is included in the electric circuit and 120

which is included in the electric circuit and 125

between which the said arm is movable, a spring strip provided upon the pendulum and pressing against the end of the pivoting shaft of the said arm, an electromagnetic system, consisting of a solenoid of small size connected to the supply circuit and by a light magnet of small size, the said magnet being mounted on the pendulum while the said solenoid is disposed in the path of the magnet, and means whereby the said electromagnetic system shall act upon the pendulum only during a time which is considerably less than the time during which the circuit remains closed, a complementary electromagnetic device exercising a retarding action upon the pendulum when at the end of its normal swing, and means for rapidly increasing the retarding action when the amplitude of swing increases, a cylindrical case made in two portions whereof one portion contains the whole of the above-mentioned elements, a clock dial constituting the front face of the said portion, the second portion containing two electric contact strips constituting the supply terminals, and a removable battery whose terminals cooperate with said supply terminals.

7. An electromagnetic clock with operating pendulum, comprising a pendulum, loops of a very hard steel wire secured to the upper part of the pendulum and parallel to its plane of oscillation, similar loops of a very hard steel wire secured to the clock frame perpendicular to the plane of oscillation of the pendulum, and engaging the first-mentioned loops, a short and light circuit-breaking arm, a pivoted shaft mounted on said pendulum very close to its suspension device, a spring mounted on the pendulum which forms part of the electric circuit and urges the said shaft upon a very small front end surface of the latter, a bearing surface of relatively large area formed at the rear end of the said shaft, a recess formed in said pendulum and containing the rear end of the shaft, a contact surface provided in said recess and coacting with the rear end of the shaft, an oil cavity formed in said rear end of the shaft, two stationary contact elements one of which is included in the electric circuit and between which the said arm is movable, a spring strip provided upon the pendulum and pressing against the end of the pivoting shaft of the said arm, an electromagnetic system consisting of a solenoid of small size connected to the supply circuit and by a light magnet of small size, the said magnet being mounted on the pendulum while the said solenoid is disposed in the path of the magnet, and means whereby the said electromagnetic system shall act upon the pendulum only during a time which is considerably less than the time during which the circuit remains closed, a complementary electromagnetic device exercising a retarding action upon the pendulum when at the end of its normal swing, and means for rapidly increasing the retarding action when the amplitude of swing increases, a cylindrical case made in two portions whereof one portion contains the whole of the above-mentioned elements, a clock dial constituting the front face of the said portion, the second portion containing two electric contact strips constituting the supply terminals, and a removable battery whose terminals cooperate with said supply terminals, a base having therein a cylindrical recess cooperating in which is disposed the above-mentioned cylindrical case containing the clockwork, a regulating magnet disposed upon the said base below the said pendulum magnet and having substantially the same length as the latter, a pivot shaft traversing one end of the said regulating magnet, the latter being movable upon the said pivot, means for securing the said magnet in each of its positions, and a graduated scale cooperating with the other end of the magnet.

In witness whereof I have hereunto set my hand.

LÉON HATOT.
